Primary Examiner — Marianne Pandozzi*Assistant Examiner* — Jae Liang(74) *Attorney, Agent, or Firm* — Griffiths & Seaton PLLC; JoAnn M. Seaton(57) **CLAIM**

The ornamental design for a cup with handles, as shown and described.

DESCRIPTION

FIG. 1 is a front perspective view of a cup with handle showing our new design;

FIG. 2 is a front view thereof, the rear view being a mirror image of the front view;

FIG. 3 is a right side view thereof, the left side view being a mirror image of the right side view;

FIG. 4 is a top view thereof; and,

FIG. 5 is a bottom view thereof.

The broken line shown in the figure drawings are included for the purpose of illustration and form no part of the claimed design.
